UNITED STATES PATENT OFFICE.

ARTHUR WARD AND THOMAS FRANKLIN PENCE, OF WEBB CITY, MISSOURI; SAID WARD ASSIGNOR TO SAID PENCE.

AUTOMATIC REGULATOR FOR AIR-COMPRESSORS.

1,176,998.

Specification of Letters Patent.

Patented Mar. 28, 1916.

Application filed April 16, 1914. Serial No. 832,335.

To all whom it may concern:

Be it known that we, ARTHUR WARD and THOMAS FRANKLIN PENCE, citizens of the United States, residing at Webb City, in the 5 county of Jasper and State of Missouri, have invented certain new and useful Improvements in Automatic Regulators for Air-Compressors; and we do declare the following to be a full, clear, and exact description 10 of the invention, such as will enable others skilled in the art to which it appertains to make and use the same.

This invention relates to air pumps, and more especially to those employed for compressing air; and the object of the same is to produce an improved automatic regulator whereby the load on an air compressor will be relieved or released at both the inlet and outlet ends of the same in the event of excessive 15 pressure in the receiver. This object is carried out by the details hereinafter more fully described and claimed and as shown in the drawings wherein—

Figure 1 is a side elevation of a constant 25 speed air compressor with our automatic regulator applied; Fig. 2 is a central vertical section of the throttle valve; and Fig. 3 is an end elevation thereof; Fig. 4 is a diagrammatic sectional view showing more 30 clearly the general arrangement of our regulator; Fig. 5 is a side elevation of the release valve; and Fig. 6 is a vertical section thereof; Fig. 7 is a vertical section of a modified form of release valve; and Fig. 8 35 is a side elevation of the same.

It is well known to those familiar with the action of air compressors that when the valves in the various cylinders commence to leak from any cause or when any other 40 untoward conditions arise the pressure in the machine increases above that to which it is desired to raise it, heat is generated and the temperature rises rapidly, and eventually gases are produced and an explosion occurs which 45 wrecks the machine and endangers the life of the operator. Experience has demonstrated the fact that these explosions occur at a time when the machine is running with the intake closed and is not making air, and therefore 50 although the usual conditions may be known to exist it is dangerous to retard the speed of the machine and stop its action because in slowing it down an explosion may occur.

It is the purpose of the present invention to 55 take the load off the machine at such times by

first reducing the inlet of air at the intake end of the machine and then relieving the machine at the outlet end thereof by releasing pressure in the last cylinder so that the compressed air and the gases referred to are delivered 60 from the high pressure cylinder or pump into the atmosphere rather than into the receiver. This object we accomplish by utilizing the excessive pressure in said receiver to actuate the devices hereinafter described, 65 and therefore to the extent that this excess of pressure is taken from the receiver the latter also is relieved of unusual strain. It results that our regulator quickly and automatically alters conditions at three points in 70 the air compressor, with the result that, whether the machine continues to run or the operator slows it down to stop it entirely, the danger of accident has been reduced to a minimum and no catastrophe will occur. 75 We find in practice that the use of this regulator frequently tides over unusual conditions, so that after it has acted and its parts are restored to their normal position, the 80 air compressor continues its work uninterrupted.

In the accompanying drawings we have shown our device as applied to a constant speed air compressor having a high pressure cylinder and a low pressure cylinder, 85 but these cylinders will be called "pumps" in the following specification in order to avoid confusion with other elements which we prefer to designate as cylinders.

The letter I has been employed to designate the intake, whence the air passes through a balanced valve or throttle T to the low pressure pump L, thence it is conveyed by the intercooler C to the high pressure pump H, and from the latter it passes 90 through the outlet O to the receiver R which carries a pop-valve or safety valve S of any well known type. The two pumps are illustrated herewith as driven by any suitable motive power M. The parts as thus far described 95 are not claimed to be new and are illustrated herewith only for the sake of showing how our improved regulator is applied.

Coming now to the details of the present 100 invention, an upright cylinder 1 is supported by a framework 2 mounted on the casing 3 of the throttle valve T, and within said cylinder moves a piston 4 which is connected with the valve stem 5 of said throttle. Through said framework 2 passes a yoke 6 105 110

secured to said stem, and the ends of this yoke are connected by springs 7 with another yoke 8 overlying the cylinder 1, so that the tendency of the springs is to raise 5 the stem and open the throttle valve T. The latter is by preference of the balanced type as shown, and when closed or partly closed it throttles the inlet through the intake pipe I, and to a greater or less degree cuts off the 10 admission of air to the low pressure pump L.

While we have shown the receiver R as provided with a safety valve S as usual, this element may be employed or not as preferred; but the outlet therefrom or the outlet 15 from the receiver R is in the present instance by means of a pipe 10 which leads into the inner end of a cylinder 11 which may well be mounted in a horizontal position 20 on the top of the cylinder 1 as shown. Said cylinder carries a piston 14 whose stem 15 projects out the end of the cylinder and contacts with a bell crank lever 13 which is pivotally mounted on a bracket supported 25 by the cylinder 11, the outer arm of this lever carrying an adjustable weight 12 as shown. This weight is set at the desired point, and it results that when the pressure in the receiver R exceeds that which the 30 weight exerts it will flow through the pipe 10 (whether the safety valve S is employed or not) and will move the piston 14 outward so that its stem rocks the bell crank lever 13 on its pivot and raises the weight. 35 The stem 15 is continued through the piston head 14 and reduced at its inner end so that it constitutes a needle as at 16, the same closing a port 17 when the weight 12 descends; and the relative arrangement of the 40 two cylinders 1 and 11 is such that this port establishes communication between the pipe 10 and the interior of the cylinder 1. The port 17 communicates with a vent 18 which is by preference formed in the head of the 45 cylinder 1 and is of quite small size. The result is that the excessive pressure within the receiver, after it has moved the piston 14 outward against the tendency of the weight 12, flows through the port 17 and 50 vent 18 into the top of the cylinder 1 above the piston 4 therein, and the latter is caused to move downward against the tension of the springs 7 so that the throttle valve T is closed to a greater or lesser degree. If the 55 excessive pressure within the receiver is small, the throttle will doubtless be closed only partly; but if the excess of pressure therein should be considerable, as it probably will be if untoward conditions arise 60 within the air compressor, the piston 4 will be borne downward and the throttle T completely closed so that thereafter the low pressure pump L is working on a vacuum. This will continue as long as the throttle is 65 closed, but the vent 18 permits the slow es-

cape of the compressed air within the head of the cylinder 1 above its piston 4, and therefore the excessive pressure within the receiver R is being relieved as long as the piston 4 is held down and the throttle is 70 closed. As soon as said excess of pressure is relieved to a sufficient extent, the weight 12 descends and the bell crank lever 13 moves the stem 15 inward so that the needle 16 closes the port 17 and cuts off the supply 75 of pressure through the pipe 10; after which the vent 18 permits the slow escape of air above the piston 4 and the latter rises under the tension of the springs 7 to re-open the throttle T and permit the machine to again 80 take air through the inlet I.

If the air compressor is of that type which employs double-acting pumps, both ends of the high pressure pump H will be connected with the outlet pipe O which leads to the 85 receiver R; and that untoward conditions in this pump may be immediately relieved it is preferred that each end of the pump shall have a relief valve whose construction 90 will now be described.

The numeral 20 designates the valve casing, one arm 21 of which is connected with the interior of the high pressure pump, and the other arm 22 of which leads to an exhaust such as the atmosphere. The valve 95 seat is formed in a bridge 23 within this casing and the valve head 24 rests upon said seat and is normally held upon the same by means of a spring 25 whose tension may be adjusted in any suitable way as by means 100 of a set screw 26. The valve is arranged to close upon its seat with the pressure which normally flows into the arm 21 and would escape out the arm 22 if the valve were open, and therefore the normal pressure 105 within the high pressure pump tends to hold this relief valve closed. Carried by the valve casing 20 is a cylinder 27 within which moves a piston 28 whose stem 29 passes upward into the casing 20 and stands 110 beneath the valve head. The lower end of the cylinder 27 is connected by a pipe 30 with a pipe line 31 which leads back past the air compressor and is tapped through 115 the side of the cylinder 1 at a point 32.

When now the excess pressure within the receiver R forces the piston 4 downward to a point where the throttle valve T is closed, some of this pressure may escape through the pipe line 31 and its branches 30 into each 120 of the cylinders 27, and the piston 28 therein is raised so that its stem unseats the valve 24 and the excess of pressure within the high pressure pump is permitted to escape into the atmosphere rather than to flow into the 125 receiver R. As soon as the excess pressure in the receiver has spent its force and the piston 4 commences to ascend under the impulse of the springs 7 (as the vent 18 permits) the reduced pressure in the upper end 130

of the cylinder 1 permits the descent of the piston 28 so that the valve 24 closes at once under the impulse of the spring 25 and the relief valve acts no longer. Continued upward movement of the piston 4 slowly opens the throttle T and gradually again admits air to the low pressure pump L. Meanwhile of course the excess of pressure within the receiver R has been relieved, and therefore 10 our regulator has acted automatically at three points within the air compressor to overcome or relieve the untoward conditions which, as shown above, often give rise to serious accidents. The setting of the weight 15 12 controls the point at which the pressure within the receiver will cause the regulator to act, and if said receiver be provided with a safety valve S the latter will doubtless be capable of adjustment in the usual manner. 20 The setting of the screw 26 controls the point at which the relief valve 24 will open, and in fact this set screw may be adjusted so tightly that this valve will not open unless the excess of air is exceedingly high. 25 This is quite safe, for the unusual conditions are generally relieved by throttling the intake and permitting an exhaust of the excess of pressure within the receiver. It is considered to be an important feature of the 30 present invention, however, that the excess of pressure from the receiver admitted to the cylinder 1 which controls the throttle valve T, shall vent itself after the same has been controlled and therefore allow parts 35 to automatically restore themselves to their normal position.

In Figs. 7 and 8 is shown a modified construction of the relief valve whose casing 40 has a globe check valve G in its inlet arm 41, its outlet arm 42 being connected with the exhaust or the open atmosphere and its bridge 43 having a valve seat for the valve head 44 which closes with the pressure from the high pressure pump. The stem 45 of 45 this valve projects upward through a two-part cylinder 46 provided internally at about its mid-length with a bridge 47 having an opening through which the stem moves loosely so that there can be a slight escape 50 of air around it. The upper end of the cylinder is closed and the pipe line 30 opens through it as shown. Adjustably mounted on the stem 45 is a nut 48, between which and the bridge within the cylinder is a 55 spring 49 tending to close the valve, while another spring 50 coiled on the stem beneath the bridge in this cylinder tends to open the valve. The action of this relief valve is substantially the same as that of the valve described above. When pressure is admitted 60

at the point 30 through the head of the cylinder 46, it bears downward on the upper end of the stem 45 which therefore serves as a piston and assists the spring 50 in opening the valve 44. When the force of this excess of pressure has been exhausted, it leaks slowly out through the opening in the bridge 47 and eventually permits the springs to restore all parts of this relief mechanism to their normal condition. 70

What is claimed as new is:

The combination with a low pressure pump, a double acting high pressure pump, an inlet into the low pressure pump, a passage member leading from said low pressure pump to the intakes of the high pressure pump, a receiving chamber, and an air outlet leading from both exhaust ports of the double acting high pressure pump to said receiving chamber, of a throttle valve for 80 the air inlet, a cylinder having therein a piston for closing said throttle valve, a tube leading from the receiving chamber into the cylinder behind the piston, means normally obstructing communication between the receiving chamber and said cylinder and adapted to be released by excessive pressure in said chamber, whereby some of such pressure may flow into said cylinder to project the piston and thus close the throttle valve, 85 a vent leading to the open air from said cylinder whereby some of the excessive pressure may escape, a pair of relief valves for the two units of the double acting high pressure pump and having compartments into which pressure must be admitted to open said valves, an additional vent from the cylinder and exposed when the piston is projected to close the throttle valve, and a branched tube leading from said additional vent to said 90 compartments, whereby to allow pressure to pass from said cylinder into the aforesaid compartments to open the relief valves and thus allow the escape of air from the high pressure pump at two points while excessive pressure is escaping through the aforesaid vent, the compartments being so constructed 95 as to allow the pressure received therein to escape, thus providing additional means for reducing the excessive pressure in the receiving chamber. 100

In testimony whereof we have hereunto set our hands in presence of two subscribing witnesses.
